UNITED STATES PATENT OFFICE.

DANIEL HILL, OF PROVIDENCE, RHODE ISLAND, ASSIGNOR TO INTERNATIONAL BRAID CO., OF PROVIDENCE, RHODE ISLAND, A CORPORATION OF MASSACHUSETTS.

LACING-TIP.

1,218,260.

Specification of Letters Patent.

Patented Mar. 6, 1917.

Application filed June 16, 1916. Serial No. 103,925.

To all whom it may concern:

Be it known that I, DANIEL HILL, a citizen of the United States, and resident of the city of Providence, in the county of Providence and State of Rhode Island, have invented certain new and useful Improvements in Lacing-Tips, of which the following is a specification.

This invention relates to an improved 10 wire tip for lacings more particularly adapted to be applied to the heavier type of lacings such as those employed for lacing portions of automobile tires and other similar heavy work, lacings of such heavy 15 construction requiring a special form of extra strong tip which cannot be removed even by the roughest handling. This tip may also be applied to shoe lacings, corset lacings and lacings for other purposes.

20 The object of this invention is to form such a tip by passing one end of the wire through the body of the lacing and laying it lengthways to the end thereof, then winding the wire in a helical coil around the 25 end of the lacing and bending or securing the ends of the wire together to positively prevent the coil from slipping from the facing.

It is found in practice that where a wire 30 tip is formed on an extra heavy stiff well-sized or starched lacing, such as for instance those used on automobile tires and in heavy boots, that the wire wound about the end to form a tip thereon will not embed itself into the fabric and therefore unless the coils are firmly and positively secured or bound together, they will loosen sufficiently to be easily withdrawn from the end of the lacing.

40 The ends of this wire may be secured together in various ways such as twisting them together, but I preferably secure and bind the ends of the wire and a number of the coils together, by applying molten solder thereto, which forms the extremity of the tip into a metal mass making a smooth end and positively preventing the wire from being withdrawn from the lacing.

Another feature of my invention is that 50 in order to form the tips on a taper I skive or cut the end of the lacing on an angle whereby when the wire is wound around the tip it is nicely tapered and reduced to a desirable point.

55 With these and other objects in view, the

invention consists of certain novel features of construction, as will be more fully described, and particularly pointed out in the appended claims:

In the accompanying drawings: 60
Figure 1— is a side view of the end of the lacing provided with my improved wire tip soldered at its end.

Fig. 2— is a side view of the end of a lacing showing the same as skive or cut 65 on an angle and showing the wire as passing through the lacing with one end extending longitudinally thereof and beyond the end of the lacing.

Fig. 3— is a diagrammatic view showing 70 the manner in which the tip is formed by winding the wire in a tapering helical coil.

Referring to the drawings, 10 designates the lacing which is usually made of silk, 75 linen or cotton braided or otherwise constructed into a flat or tubular form.

My improved tip 11 for the lacing is formed of wire and wound in a helical form about the extremity of the lacing.

It is found in practice in the forming of 80 tips, particularly in forming of tips on lacings of extra heavy construction and which are hard laid and have received an extra coating of size or starch that the coils of wire wound thereon will not embed themselves sufficiently into the surface of the fabric to readily adhere thereto, and it is found to be extremely difficult to prevent the wire from pulling or being drawn from the end of such a lacing. Therefore to provide practical and effective means for securing a wire tip to the lacing, I first pass the end 12 of the wire through the fabric at the point 13 where the coil begins and lay this portion of the wire longitudinally on 85 the fabric to extend to and beyond its adjacent end. The edges of the flat fabric are then folded inward as at 14 and the wire wound in a close helical coil about the same as shown in Fig. 2 and beyond the end of 90 the fabric a few turns being made as at 15 about the opposite end 12 of the wire.

In order to secure these portions of the wire together, I preferably apply a molten solder thereto, and then cut off the ends thus forming a smooth reduced point or end 16 to the tapering tip as illustrated in Fig. 1 by which construction it will be seen, that not only are a number of the coils soldered together, but a number of these coils are also 110

soldered to the portion 12 of that portion of the wire which is anchored at the point 13 in the fabric, thus effectually preventing any possibility of uncoiling, unwinding or the 5 slipping of the coils from the fabric causing the tip to firmly adhere to the fabric regardless of whether or not the coils are deeply embedded into the surface thereof.

It is found in practice that where the lac- 10 ing is very heavy that it is desirable to skive or cut its end on the bias or on an angle as at 18, see Fig. 2, whereby the winding of the wire about the same produces a nicely tapered effect thus forming a tip which is 15 handsome and attractive in appearance with a smooth and nicely reduced entering point or end and one which is strong and durable and that is firmly anchored to the fabric.

Having thus described one illustrative 20 embodiment of my invention I desire it to be understood that although specific terms are employed they are used only in a generic and descriptive sense, the scope of the invention being defined and limited only by 25 the appended claims.

Copies of this patent may be obtained for five cents each, by addressing the "Commissioner of Patents, Washington, D. C."

I claim:

1. A lacing having a tip consisting of a wire attached to the lacing and provided with a longitudinally disposed strand, a portion of said wire being helically coiled 30 around said strand, a plurality of the convolutions of the coil at the extremity thereof being soldered together and to said strand.

2. The combination with a lacing having 35 its end skived off at an angle and folded longitudinally, of a tip consisting of a wire attached to the lacing and provided with a longitudinally disposed strand, a portion of said wire being coiled helically around said 40 folded portion and said strand, and a plurality of the convolutions of the coil at the extremity of the tip being soldered together and to said strand.

In testimony whereof I affix my signature 45 in presence of a witness.

DANIEL HILL.
